UNITED STATES PATENT OFFICE.

RAYMOND CARPENTER, OF EAST ORANGE, NEW JERSEY, ASSIGNOR TO THE GRISCOM-RUSSELL COMPANY, A CORPORATION OF DELAWARE.

STEAM-SEPARATOR.

1,243,258.

Specification of Letters Patent. Patented Oct. 16, 1917.

Application filed July 10, 1915. Serial No. 39,063.

To all whom it may concern:

Be it known that I, RAYMOND CARPENTER, a citizen of the United States, residing at East Orange, county of Essex, and State 5 of New Jersey, have invented certain new and useful Improvements in Steam-Separators; and I do hereby declare the following to be a full, clear, and exact description of the invention, such as will enable others 10 skilled in the art to which it appertains to make and use the same.

This invention relates to steam separators for use in extracting particles of water or other liquids from steam. The invention is directed to the provision of an improved form of separator which is reliable and efficient in operation, which is of simple construction, and which may be manufactured at relatively low cost.

20 In steam separators as heretofore constructed, it has been common to cause the steam to flow against one or more baffles upon which the liquid particles impinge so as to become separated from the steam. 25 Also, it has been common to cause the steam to assume a circular flow in order that the liquid particles will be thrown off by centrifugal force. The separator constructed in accordance with the present invention 30 differs from these prior types primarily in that it is so constructed as to cause the steam to be divided into two or more streams which are subsequently caused to flow into each other. As a result of this, the particles of liquid in the steam drop to the 35 bottom of the separator and then pass off through a suitable drip connection. Preferably, a vane or blade is employed in the path of the incoming steam adapted to divide the steam into two streams and curved walls guide these two streams in circular paths so as to cause them to flow into each other. While the steam is flowing in this 40 manner, more or less of the liquid particles contained therein are extracted due to the impingement of liquid particles upon the vane and also to the centrifugal force exerted upon the liquid particles while they are flowing in the curved path. Then, when 45 the two streams meet, they arrest each other momentarily as a result of which particles of moisture remaining in them may drop by gravity and liquid deposited upon the wall of the separator may flow down-

wardly to the water outlet instead of being 55 carried along by the stream.

Provision for the flow of steam through the separator in the manner above indicated is preferably made by providing an inlet 60 passage for the steam extending within a casing of substantially cylindrical form and located eccentrically with respect to the casing. This inlet passage has an opening on one side thereof and opposite this opening is a vane or blade employed for dividing 65 the incoming steam into two streams. The opening in the inlet passage is located on the side of the passage which is nearest to the side of the casing, so that the two paths for the steam flowing from the vane around 70 the casing to the outlet are paths of constantly increasing area. As a result of this, the velocity of the steam in its flow from the vane around to the outlet is greatly decreased and the separation of liquid particles from the steam therefore takes place 75 more effectively. Furthermore, the outlet passage for the steam extends into the casing of the separator a substantial distance to more effectively guard against the passage 80 of particles of liquid into the outlet opening, particularly particles which have been thrown out upon the wall of the casing.

The preferred embodiment of the invention is illustrated in the accompanying 85 drawings, in which Figure 1 is a top view of apparatus embodying my improved form of separator, the separator being shown in horizontal section on line 1—1 of Fig. 2, and Fig. 2 is a view partly in central vertical 90 section of the apparatus shown in Fig. 1.

In the drawings, I have illustrated my improved form of separator as applied to an evaporator of the type adapted for use in evaporating salt water to obtain water which 95 is free from salt. The evaporator shown consists of a casing 3 of substantially cylindrical form adapted to have salt water admitted thereto. Within the casing are a plurality of coils of pipe 4 through which steam is caused to flow to vaporize the water within the casing. The steam rising from the water within the casing passes around a baffle 5 and into the separator which is located on top of the casing 3.

The separator shown is in the form of a dome mounted on top of the evaporator and consists of a cylindrical casing 6 closed at its

upper end 7. The lower end of the casing 6 is provided with a flange 8 to facilitate attachment of the separator to the casing of the evaporator over an opening in the latter. Within the casing 6 is an inlet passage 9 for the steam rising from the evaporator. The walls of this passage are secured to or formed integral with those of the casing 6 and the passage 9, or at least the upper portion thereof, is located eccentrically with respect to the casing 6, as is clearly shown in Fig. 1. The inlet passage 9 has an opening located in the side thereof which is closest to the wall of the casing 6; preferably the side walls of this opening are curled outwardly, as shown at 10 in Fig. 1. Directly opposite this opening in the side of the inlet passage is a vane or blade 11, V-shaped in horizontal cross section and having the apex of the V located opposite the center of the opening in the wall of the inlet passage 9. The walls of this V-shaped blade merge into the side walls of the casing 6, the construction being such that steam flowing through the opening in the inlet passage 9 is divided by the vane 11 into two streams which are deflected laterally and caused to flow in semi-circular paths around the side walls of the casing 6.

The outlet for the steam from the separator is located upon the side of the inlet passage 9 opposite that in which the opening above described is provided. This outlet consists of a tubular member 12 projecting inwardly from the wall of the casing 6 and a pipe 13 forming a continuation of the tubular member. It will be noted that the tubular member 12 projects inwardly from the wall of the casing 6 a substantial distance so that water which has impinged upon the side wall of the separator cannot be carried into the outlet opening.

The separated water and other liquid passes downwardly within the separator and is deposited upon the inclined bottom wall 14 thereof over which it flows to the drip opening 15. This drip opening is extended downwardly by a pipe 16 to a point below the level of the liquid within the casing 3 of the evaporator.

In operation, the steam rising from the water within the casing 3 passes around the baffle 5 and into the tubular inlet passage 9. From this passage the steam passes through the opening and is divided by the vane 11 into two streams which flow in opposite directions around the side walls of the casing 6. As the stream passes out of the inlet opening and into the separator proper, many of the particles of liquid carried by the steam impinge upon the walls of the vane 11 and the adjacent side walls of the separator and these particles pass downwardly by gravity to the bottom of the separator.

Also, as the steam is flowing around its semi-

circular courses from the vane 11 to the outlet 12, the particles of liquid contained therein are subjected to centrifugal force which tends to throw them outwardly and deposit them upon the side walls of the separator upon which they flow downwardly by gravity. It will be noted that by reason of the eccentric location of the inlet conduit 11 with respect to the cylindrical casing 6, the paths for the steam from the vane 11 around to the outlet 12 are paths of steadily increasing area so that as the steam flows around these paths its velocity is gradually decreased. This decrease of velocity facilitates the separation of the particles of liquid from the steam. In the region of the outlet opening 12, the two streams of steam flow into each other and mutually arrest each other so that particles of liquid remaining in the steam are allowed to drop by gravity to the bottom of the separator. The steam itself, then freed from the water contained therein, passes out through the outlet consisting of the tubular member 12 and the piping 13 leading from that member. Since the outlet member 12 is extended into the casing 6 of the separator, water which has collected upon the wall of the separator will not be carried by the steam into the outlet opening where it would be again taken up by the steam. The water separated from the steam collects in the bottom of the separator and passes out through the pipe 16 to the body of water within the evaporator.

It will be noted by reference to Fig. 2 that the lower end of the inlet opening 9 extends below the bottom wall 14 of the separator. This extension of the inlet opening serves as a baffle to prevent splashing and surging of the water within the evaporator and is of special utility for this purpose in apparatus for use on ship board. Such a downward extension of the inlet 9 below the bottom wall 14 makes it permissible to omit the baffle 5 below the separator in some instances, particularly when the evaporator is of relatively small size so that splashing and surging of the water therein takes place to a less extent. These and other modifications of the construction herein illustrated and described, I consider within the scope of my invention and I aim to cover all such modifications by the terms employed in the claims appended hereto.

What I claim is:

1. A steam separator comprising a drum or analogous vessel having eccentrically supported within it a steam inlet with an opening facing the near wall of the drum, means for directing the steam passing from the steam inlet through the opening against the drum wall in two substantially unobstructed streams of enlarging area and decreasing velocity around the circumferential face of said wall until they are

rested by meeting one another, and an outlet passage for the dry steam.

2. A steam separator comprising a drum or analogous vessel having eccentrically supported within it a steam inlet with an opening facing the near wall of the drum, means for directing the steam passing from the steam inlet through the opening against the drum wall in two substantially unobstructed streams of enlarging area and decreasing velocity around the circumferential face of said wall until they are arrested by meeting one another, and an outlet passage for the dry steam located at a point opposite the point at which the steam is discharged against the wall.

3. A steam separator comprising a drum or analogous vessel having a substantially continuous circumferential wall, means for directing the fluids to be separated against the face of said wall, a projection on said wall substantially opposite the middle of the inlet opening for separating the fluids to be separated into two streams and directing such streams in opposite directions around the face of said circumferential wall, and an outlet passage for the steam having its opening at a point within and removed from said circumferential wall.

4. A steam separator comprising a drum or analogous vessel having a substantially continuous circumferential wall, means for directing the fluids to be separated against the face of said wall, a projection on said

wall substantially opposite the middle of the 35 inlet opening for separating the fluids to be separated into two streams and directing such streams in opposite directions around the face of said circumferential wall, and an outlet pipe for the steam projecting 40 through the wall of the drum opposite the point at which the fluids to be separated are discharged against the wall with the opening into the pipe away from the wall of the drum. 45

5. A steam separator consisting of a drum of substantially circular cross section, an inlet passage for the fluids to be separated projecting longitudinally into said drum, said inlet passage opening radially adjacent one side wall of said drum, a projection on said side wall opposite said opening for directing the fluids to be separated in two streams in opposite directions around the inner wall of said drum whereby said 55 streams will come together at the opposite side of said drum, and a discharge pipe for the steam projecting through the wall of the drum opposite the said projection, the opening into the pipe being spaced away 60 from the wall of the drum whereby the water in the two streams will adhere to the wall of said drum through its greater centrifugal force while the steam will be drawn away from the wall by the suction of the 65 discharge pipe.

In testimony whereof I affix my signature.
RAYMOND CARPENTER.
